UNITED STATES PATENT OFFICE

149,273

DESIGN FOR AN ADVERTISING PLAQUE

Charles Kompas, Milwaukee, Wis.

Application June 3, 1946, Serial No. 130,362

Term of patent 7 years

(Cl. D1—12)

To all whom it may concern:

Be it known that I, Charles Kompas, a citizen of the United States, residing in Milwaukee, in the county of Milwaukee and State of Wisconsin, have invented a new, original, and ornamental Design for an Advertising Plaque, of which the following is a specification, reference being had to the accompanying drawing, forming a part thereof.

I claim:

The ornamental design for an advertising plaque, substantially as shown.

CHARLES KOMPAS.
